UNITED STATES PATENT OFFICE.

CHARLES F. PYM, OF ESSEX, ONTARIO, CANADA, ASSIGNOR OF ONE-HALF TO KRENTLER-BROTHERS COMPANY, OF DETROIT, MICHIGAN, A CORPORATION OF MICHIGAN.

TACK PULLER AND LIFTER FOR LASTED SHOES.

No. 859,107.

Specification of Letters Patent.

Patented July 2, 1907.

Application filed August 1, 1906. Serial No. 328,690.

To all whom it may concern:

Be it known that I, CHARLES F. PYM, a citizen of Canada, residing at Essex, in the Province of Ontario, have invented an Improvement in Tack Pullers and Lifters for Lasted Shoes, of which the following description, in connection with the accompanying drawings, is a specification, like letters on the drawings representing like parts.

My invention is a machine for preparing a lasted shoe for the sewing operation. Such a shoe has the shoe upper drawn tightly over the last and tacked down closely in order to hold the stretched leather in place until it has set. The tacks, however, are in the way of the needle of the sewing machine, so that it has heretofore been customary for the operator to draw out the tacks, usually by hand, and as he progressed in drawing the tacks he has usually driven in here and there a stay tack to hold the upper in place with relation to the innersole on the last, about four such stay tacks being usually driven in. This drawing of lasting tacks and driving of stay tacks is laborious and objectionable, the operator usually carrying the lasting tacks in his mouth, which is thereby lacerated, and also the work is quite fatiguing, and is a job which workmen dislike. Accordingly in my invention I do away with the stay tacks altogether. I provide mechanism for drawing out those tacks which are unnecessary and simply lifting such tacks as should remain for staying purposes, the lifted tacks taking the place of the previously used stay tacks and being merely lifted sufficiently so as not to interfere with the sewing operation. I provide a channel opener, which also serves as a workrest, and adjacent thereto I provide a knife or ledge which coöperates with a rapidly reciprocating trimming knife, which operates to trim the projecting edge of the leather as the tacks are being pulled, thereby preparing the shoe to the best advantage for being sewed.

The constructional details of my invention will be pointed out more at length in the course of the following description taken in connection with the accompanying drawings, in which I have shown a preferred embodiment of the invention.

In the drawings, Figure 1 represents in side elevation a sufficient portion of my machine to make my invention readily understood; Fig. 2 is a top plan view thereof; Figs. 3 and 4 are transverse sectional views on the lines 3—3 and 4—4, Fig. 2, showing details of construction; Fig. 5 is an enlarged fragmentary view in side elevation, at the tack pulling and lifting region of the machine; and Fig. 6 is an enlarged fragmentary sectional view of the same region, showing the tack-engaging claws and trimming knives in top plan and in their retracted positions.

On a suitable pedestal 1 is a base 2 carrying standards 3, 4, the former supporting a drive shaft 5 operated by a

pulley 6 and the latter having guides 7, 8, 9, for a reciprocating knife carrier 10 and carriers 11, 12, to which are secured at their forward ends a pulling claw 13 and lifting claw 14, a trimming knife 15 being fast on the carrier 10. As herein shown, the carriers 11, 12, are operated by cams 16, 17, on the shaft 5 and the trimming knife 15 is operated by a link 18 pivotally connected to the carrier 11 of the lifter claw and the carrier 10 of the knife, although I wish it understood that I have connected the parts in this way merely as a preferable construction, but do not intend to limit myself thereto, inasmuch as each reciprocating part may have its own cam or other actuator and may be driven at the same or different relative speed from that shown. The carrier 11 is supported at its forward end by a pivot link or arm 19, while a similar arm 20 supports the carrier 12, being set preferably back nearer the main drive shaft 5 than the link 19, so as to cause the puller 13 to have a greater upward swing or movement at its front or claw end. I have made the discovery that a reciprocating sharp claw will pull out tacks completely, while a claw that is dull, going with the same rapidity, will only partly pull the tacks, and accordingly it will be seen, viewing Fig. 5 more particularly, that I have made the claw 14 dull or blunt, and have made the claw 13 sharp. To still further place those tacks which are merely lifted in the best position for the convenience of the operator during the sewing operation, I have provided a controlling device for the tack which is only partly pulled, that will prevent its being raised above a desired height, said device being herein shown as a post 21 having a hollowed lower end with a projecting lip 22 whose inner surface curves angularly, as shown clearly in Fig. 5, thereby coöperating with the lifting claw 14 to deflect or bend the head of the lifted tack inwardly or toward the channel, and hence away from interference with the sewing machine.

As already noted, the path of movement or lift of the tack lifter is smaller or less than that of the tack puller, so that the movement of the lifter serves merely to raise the tacks against the controller 21, which retards the front edges of the heads of the tacks as the lifter or claw 14 gives a final up-lift to the back edges of the heads, and then draws back, the result being that the tacks are bent over as shown in Figs. 5 and 6. The combined action stops their entire withdrawal just as the lifter backs wholly away from them. To still further position or control the partial withdrawal of the tacks, I provide a workrest in the form of a frame 23, adjustably secured at 24 by a screw and nut 25 to an overhanging arm 26 of the machine, said rest 23 having at its lower end one or more teeth for providing a serrated or notched edge 27 adapted to bear over a considerable surface of the inner sole of the shoe being lasted, so as to hold the same positively against improper movement, said lower end of the rest carry-

ing a channel opener in the form of a projecting prong or finger 28. Mounted on this rest arm or hold-fast 23 is a cutter blade or plate 29 pivoted thereto at 30 and adjustably secured at 31 so as to have its forward cutting edge 32 swing accurately up or down to coöperate exactly with the cutting point of the trimmer knife 15 as the latter reciprocates rapidly during the progress of the work.

It will be understood that I have purposely omitted 10 various details of construction so as to present my machine in the simplest form possible. The guides 9 serve to take up side-play and to hold the carriers 11, 12 in accurate alinement, as will be clearly evident viewing Fig. 4. Viewing Fig. 3, it will be seen that 15 the suspending links for said carriers are arranged in double pairs, pivoted to the opposite sides of the carriers, as by bolts 33, 34, which secure the links 20 to a laterally overhanging neck or portion 37 of the bracket 4.

20 In use, the operator manipulates the shoe in the usual way against the workrest or hold-fast 23, so as to permit the constantly and rapidly reciprocating tack puller 13 to pull all the tacks which he considers it advisable to pull, and so as to bring the lifting claw 25 14 into engagement with such tacks here and there as he deems it advisable to lift merely, so as to leave them in their lifted and bent-over condition to operate in place of the usual stay tacks which have heretofore been employed. The tack lifter claw engages the 30 shoe near or against the channel lip, and because of its downwardly bent, dull end, the operator can easily manipulate the shoe so as to readily lift deep-set tacks at will, or he can so hold the shoe as to bring the claw 13 into engagement with the tack and thereby entirely pull the tack, meanwhile so regulating the position of the shoe as to cause the projecting edge of the upper to be trimmed either close or long, as desired. In some cases it is desirable to have the tack puller move more rapidly than the tack lifter, and it will 35 40 also be understood that the orbit of movement may readily be changed by correspondingly shifting the links or in any other way shortening the leverage of one or the other of the claw carriers. If the operator wishes the tacks lifted more or less he regulates it by 45 adjusting the workrest, and can vary to a slight extent the position into which the tack is bent, by turning and adjusting the control or stop 21.

It will be understood that I am not limited to the 50 constructional details herein shown, as I consider my invention broadly new in having entirely eliminated the necessity of using separate stay tacks. By this means I have succeeded in providing means for accomplishing entirely by an automatic power machine the results which have hitherto been accomplished 55 by hand. In order to accomplish this result I have done away with the entire withdrawal of all the tacks and the insertion of stay tacks, and instead thereof I withdraw only such tacks as can be readily dispensed with, and the remaining tacks I put in such position 60 that they do not interfere with the subsequent sewing of the shoe. I regard my invention as broadly novel in the provision of means for accomplishing this result. Therefore I intend to include within the terms of my broader claims any and all forms of tack lifting means 65 and any and all forms of tack pulling means, etc. I

have timed the parts so that the knife cuts the upper just before the lifter raises a tack and hence the upper is still held fast while being cut, and hence the shoe can be fed by the workman either to the right or to the left, according to his preference.

Having described my invention, what I claim as new and desire to secure by Letters Patent, is,

1. In a machine of the kind described, power driven means for engaging a tack, and actuating means therefor, said engaging means and its actuating means being constructed and arranged to lift the tack only partially from the shoe.

2. In a machine of the kind described, a work rest for controlling the height of a lasted shoe, a rapidly operating tack puller for pulling lasting tacks from the upper, and tack lifting means operating only to partially remove certain of the tacks from the shoe, said tack puller and tack lifting means being constructed and arranged to coöperate close to each other progressively together about the periphery of the shoe as the shoe is moved along said work rest, and common actuating means for said two tack engaging devices.

3. In a machine of the kind described, the combination with rapidly operating tack pulling mechanism, of tack lifting mechanism, and a common actuating means for both of the tack engaging devices, including means for moving the said lifting mechanism a less vertical effective distance than the pulling movement of said tack pulling mechanism, said tack puller and tack lifting means being constructed and arranged to coöperate close to each other progressively together about the periphery of the shoe as the shoe is moved along said work rest.

4. In a machine of the kind described, the combination with a work rest constructed to permit a shoe to be pivotally manipulated thereon with relation to the herein-after mentioned two tack-dislodging devices, of two tack-dislodging devices located close to and opposite said work rest arranged to operate close to each other progressively along the same line of tacks, and operating mechanisms for said two devices, including means for transmitting to one of said devices a short tack-moving movement and means for transmitting to the other of said devices a longer tack-moving movement.

5. In a machine of the kind described, the combination of two tack-dislodging devices arranged to operate close to each other along the same line of tacks, one of said devices consisting of a dull edged claw, and operating mechanisms for actuating said dull edged claw sufficiently merely to lift but not remove certain of the tacks and for actuating said other device to remove the remaining tacks.

6. In a machine of the kind described, the combination of a tack lifter, power actuating means therefor, and co-operating means for causing said lifter to bend or deflect a tack from its normal position and to release the tack when only partially withdrawn.

7. In a machine of the kind described, the combination with a tack lifter, and actuating means therefor, of means for stopping the withdrawal of a tack when partially removed from the shoe.

8. In a machine of the kind described, the combination with a tack lifter and power actuating means therefor of a controlling device for limiting the extent of removal of the tack by said tack lifter.

9. In a machine of the kind described, the combination with a tack lifter and power actuating means therefor of a controlling device for limiting the extent of removal of the tack by said tack lifter, said controlling device having a deflecting surface for coöoperating with said tack lifter to bend the head of the tack laterally in the shoe.

10. In a machine of the kind described, the combination with means for pulling tacks from a lasted shoe, of a work rest adapted to occupy the innersole channel adjacent said pulling means, provided with a stationary cutting edge, and a reciprocating cutter operated to reciprocate in unison with said tack pulling means to trim the upper against the cutting edge of said workrest.

11. In a machine of the kind described, the combination with a continuously operated tack lifter, of a work rest

provided at its engaging end with a channel opener prong against which the operator can pivot the shoe at its channel, and means arranged opposite said prong to operate in opposition to said tack lifter, to engage the upwardly moving tack and stop the vertical movement of the tack.

12. In a machine of the kind described, the combination of two tack moving devices in operative proximity, constructed and arranged to enable the operator, at will, and in the normal progress of the work, either to remove or 10 partially lift tacks as his judgment determines, to prepare

the shoe for the sewing machine by practically a single manipulation, and operating mechanism for operating said two devices.

In testimony whereof, I have signed my name to this specification, in the presence of two subscribing witnesses. 15
